(57) **CLAIM**

The ornamental design for a side gusseted flexible beverage pouch with shaped body, as shown and described.

DESCRIPTION

FIG. 1 is a forward perspective view of my design of a side gusseted flexible beverage pouch with shaped body illustrating the characteristic features of the design which resides in its shape together with having an opaque upper portion and transparent lower portion on both the front, back, left and right sides of the pouch;

FIG. 2 is a front elevational view of the embodiment illustrated in FIG. 1, the rear elevational view being identical;

FIG. 3 is a left side elevational view of the embodiment illustrated in FIG. 1, the right side elevational view being identical;

FIG. 4 is a bottom view of the embodiment illustrated in FIG. 1; and,

FIG. 5 is a top view of the embodiment illustrated in FIG. 1.
